US00D924697S

(12) **United States Design Patent** (10) Patent No.: **US D924,697 S**
 Peng et al. (45) Date of Patent: **** Jul. 13, 2021**

(54) **CLOCK**

(71) Applicant: **SHENZHEN VANTOP TECHNOLOGY & INNOVATION CO., LTD.**, Shenzhen (CN)

(72) Inventors: **Yiya Peng**, Shenzhen (CN); **Huorong Zhong**, Shenzhen (CN); **Dawei Wang**, Shenzhen (CN)

(73) Assignee: **SHENZHEN VANTOP TECHNOLOGY & INNOVATION CO., LTD.**, Shenzhen (CN)

(**) Term: **15 Years**

(21) Appl. No.: **29/768,870**

(22) Filed: **Feb. 2, 2021**

(51) LOC (13) Cl. **10-01**

(52) U.S. Cl. .... **USPC D10/15**

Primary Examiner — Katherine Glennon

(57) **CLAIM**

The ornamental design for a clock, as shown and described.

DESCRIPTION

FIG. 1 is a perspective view of a clock showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the clock that form no part of the claimed design.

1 Claim, 8 Drawing Sheets
